CONTROL APPARATUS FOR POWER-
OPERATED GUN MOUNTSFred C. Eastman, Marblehead, Mass., assignor to
United Shoe Machinery Corporation, Flemington,
N. J., a corporation of New Jersey

Application August 16, 1946, Serial No. 690,910

4 Claims. (Cl. 89—41)

1

This invention relates to control apparatus, and more particularly to apparatus for controlling a fluid pressure system in which power may be exerted because of an initial manual movement of a handle to secure a desired objective after which the mechanism provides an automatic tendency for the handle to be retracted a distance dependent upon the extent of the initial manual movement. This retraction gives rise to a simultaneous and corresponding reduction or increase in the power applied, thereby aiding an operator in his efforts quickly to attain and yet not going beyond the desired objective in applying the power. The invention is herein illustrated as embodied in control mechanisms for fluid pressure systems of power operated gun mounts, but it will be understood that the invention in its more general aspect is not thus limited in its applicability.

When fluid pressure systems are used to transmit power with accuracy and sensitiveness as in the case of power operated gun mounts of the airplane type, it is clearly essential that the operator obtain his desired objective as quickly as possible. He ordinarily must make two motions of his manual control—one motion to enable the fluid pressure system to swing the gun at such a rate as to "catch up" with a relatively moving target and the other to retard that rate as the gun is correctly trained upon the target. If the gun barrel is swinging faster than required, then the operator must retard the rate at which it is swinging and yet not retard it too much. The time increment involved is of vital significance especially in modern aerial warfare in which a single combat action is usually of few seconds' duration.

It is an object of this invention to provide an apparatus for aiding an operator of a power system to control the system with a high degree of promptness and accuracy. It is a further object of the invention to provide in a fluid pressure power system a control for aiding an operator which control will automatically tend to correct a given rate of power application and simultaneously acquaint the operator of such tendency and its magnitude by means of a resilient force exerted upon a manually operated handle.

Two embodiments of the present invention are herein illustrated, each of which, for the purposes in view and in accordance with various novel features of the invention is provided with a control apparatus for a fluid pressure system in which control handle means is arranged to open and close a valve in the system and an automatic device associated with the handle tends to im-

2

part to the handle and valve retracting movements of predetermined extent which are proportional to their initial or preceding movements. One embodiment is provided with a purely mechanical control utilizing a friction block and rocking lever to secure the desired retraction of whatever initial movement is imparted to a control valve of the fluid pressure system. The other embodiment is provided with a combined electrical and mechanical control utilizing universally pivoted control handle means located in a fixed position with a motor driven cam and sliding contacts for opening and closing an electrical circuit in accordance with the angle to which the handle means is turned and the circuit controlling a solenoid-operated valve in a fluid pressure system.

The above and other features of the invention including novel details of construction and combinations of parts will now be more particularly described in connection with the accompanying drawings and pointed out in the claims.

In the drawings,

Fig. 1 is a side elevational view of a gun mount incorporating one embodiment of the invention;

Fig. 2 is a rear view (drawn on a larger scale) of one of the control devices shown in Fig. 1 with a rear face plate removed for purposes of illustration;

Fig. 10 is a plan view, somewhat enlarged, of a portion of the structure shown in Fig. 1;

Fig. 11 is a sectional view along the line XI—XI of Fig. 10 with some parts rotated 90 degrees for ease of illustration;

Fig. 12 is a perspective view of a peculiarly shaped element per se, this element being one of the parts in the assembled structure of Figs. 4, 5 and 6;

Fig. 13 is a perspective view of the mechanism for supporting the gun for movement in azimuth and elevation with portions of related parts assembled therewith;

Fig. 14 is a perspective and enlarged view of the operating handle shown in Figs. 1 and 10;

Fig. 15 is a view in elevation of a gun mount installed in the fuselage of an airplane, the mount being provided with a second embodiment of the control mechanism incorporating the present invention;

Fig. 16 is an enlarged elevational view of the control handle casing of Fig. 15 with a part of the casing cut away and with the handles in normal of non-operating positions in so far as the gun is concerned;

Fig. 17 is a plan view of the control handles and box shown in Fig. 16, the box portion being sectioned along the line XVII—XVII of Fig. 16;

Fig. 18 is a sectional view along the line XVIII—XVIII of Fig. 17;

Fig. 19 is a sectional view along the line XIX—XIX of Fig. 16;

Fig. 20 is an end view in elevation of the control handles and box shown in Fig. 16, part of the box being sectioned for ease of illustration;

Fig. 21 is an enlarged view in elevation, partly in section, of a control valve shown in Fig. 15;

Fig. 22 is a sectional view along the line XXII—XXII of Fig. 21;

Fig. 23 is a bottom view of the control valve shown in Fig. 21;

Fig. 24 is an enlarged view of some of the structure shown in Fig. 17 illustrating the principles of operation;

Fig. 25 is a view similar to that of Fig. 24 but further illustrating the mode of operation; and

Fig. 26 is a diagrammatic representation of the electrical connections for the gun mount of Fig. 15.

As is set forth above, apparatus illustrating the first embodiment of the invention is shown in Figs. 1 to 14, inclusive, Figs. 1 and 10 showing the general arrangement.

In Fig. 1 a machine gun 10 is shown mounted upon an adapted frame 12 supported by pins 14 and 16 (Figs. 10 and 13) which pins serve as pivots or trunnions for the gun on brackets 18 and 20 formed as parts of a forked member 22 having an integral shaft 23 journaled in a vertical gun post 24. The member 22 is retained in position by a screw 25 engaging a slot 27 on the shaft 23 and an arm 29 extends from the member 22 for a purpose to be described. Beneath the arm 29 and shoulder portions of the member 22 and rigidly affixed to the post 24 in nonrotative relation is a right angle bracket 30 (Figs. 10 and 13). This bracket 30 serves as a supporting means for one end of a piston rod 32, as will be described. Pivoted on pins 34 and 35 (Fig. 13) on the exterior end of the right angle bracket 30 is a fluid pressure cylinder 36 with a piston 38 in slidable relation therewith and attached to the piston rod 32, the latter being pivoted by a pin 33 to the arm 29. The cylinder 36 is provided with ports (not shown) for the admission and discharge of pressure fluid to and from the chamber on either side of the piston 38.

On the left side of the forked member 22 (as viewed by an operator) is pivoted at 40 a vertical fluid pressure cylinder 42 similar to the horizontal fluid pressure cylinder 36. This cylinder is provided with a vertical piston rod 44 (Fig. 1) pivoted at its upper end 46 to the gun adapter frame 12. It will be noted that the upper end 46 of the piston rod 44 is forward of the pins 14 and 16.

At the rear end of the gun adapter frame 12 is a box-like structure 50 (Fig. 10) rigidly attached

to the adapter frame 12 and bearing a rigidly mounted cylindrical handle 52. This handle merely serves as an aid for the operator to steady himself in manipulating the controls, although the trigger mechanism (forming no part of the present invention) may be associated therewith.

On the left-hand side at the rear end of the gun adapter frame 12 is mounted a frame 54 having an angle bar 56 (Fig. 14) as a top member and an angle bar 58 as a bottom member. Pivoted in the two bars 56 and 58 is a vertical rod 60 having a rigid and integral crossbar 62. At the top of the rod 60 an arm 64 is fastened by welding or otherwise, this arm bearing at its end a ball and socket unit 66 connected to a rod 68. About and spaced from the rod 60 is bent a handle or open ended shield 70 having a substantial clearance from the rod 60 at its top and bottom and being provided with bosses 72 and 74 serving as bearings for the ends of the crossbar 62. The handle or shield 70 is of one piece and at its bottom it extends downwardly in the form of a loop 76 to support a ball-and-socket joint 80 beneath the bar 58 as a connection with a rod 82.

To a midpoint of the rod 68 leading from the handle 70 a block 84 is affixed and this block has a vertical slot 86 (Fig. 10) for a purpose to be described. The rod 68 is connected by a second ball-and-socket joint 90 to an arm 92 of a dual valve generally indicated at 94 in Figs. 1, 10 and 11.

The second rod 82 leading from the handle 70 carries a block 93 similar to the block 84 of the rod 68, this block having a vertical slot 96. The rod 82 is connected by a second ball-and-socket joint 98 (Fig. 1) to an arm 100 of the dual valve 94.

The body of the dual valve 94 is provided with two parallel cylindrical chambers 102 and 104. The chamber 102 has two ports 106 and 108 and the chamber 104 has two ports 110 and 112. Each of these four ports may be annular in form but are not necessarily so. Between the two chambers 102 and 104 and parallel to them is an exhaust passage 114 communicating by means of a passage 116 with one end of each of the chambers 102 and 104 and by means of another passage 118 with the other ends of those chambers. The exhaust passage 114 is provided with a port 120 leading from the valve body. Parallel with the exhaust passage 114 and the two chambers 102 and 104 is a fluid supply passage 122 having an inlet port 124 and this passage 122 leads into the chamber 102 at 126 and also into the chamber 104 at 128. It will be noted that the point 126 is between the ports 106 and 108 of chamber 102 and that the point 128 is between the inlet ports 110 and 112 of the chamber 104. The end of the chamber 102 is closed by a screw plug 130 and the end of the chamber 104 is closed by a screw plug 132. Screwed into one end of the chamber 102 is a recessed plug 134 through which a valve stem 136 extends in slidable relation. The valve stem 136 carries two valve lands 138 and 140 corresponding respectively with the ports 108 and 106. The valve stem 136 also carries a crosspin 142 the ends of which pass through vertical slots 144 (only one slot shown) formed in the opposite sides of the recess in plug 134 and also into oppositely inclined slots 146 of a sleeve member 150 rotatable on the plug 134. The arm 92 is tightened upon the sleeve 150 and fastened to rotate therewith by means of a conventional slot-and-screw connection (only part of the slot is shown). Arm 92 and the sleeve 150 are retained upon the screw

plug 134 by a cap 152 threaded at 154 into the recess of the plug 134.

The chamber 104 is provided with parts similar in all respects to those of the chamber 102 but for convenience the valve stem is designated as 160 and the valve lands as 162 and 164.

As sensitivity of control is an essential feature in many installations and advantageous in all cases, the sensitivity of the control mechanism of Figs. 1 to 14 is illustrated by the fact that a gun has been accurately controlled by that mechanism and in which mechanism the valve spindles were moved in increments of one thousandth of an inch each way.

The end of the arm 82 bears a ball 166 forming a part of the ball-and-socket joint 90 (Fig. 10) of the rod 68. The end of the arm 100 bears a ball 168 forming a part of the ball-and-socket joint 98 (Fig. 1) of the rod 82.

Pressure fluid for operating the gun mount is taken from any convenient source of supply such as the pressure fluid system of an airplane and is directed by a flexible conduit 170 (Fig. 1) to the port 124 of the dual valve. Fluid is exhausted from the gun mount and back to the source of supply by a flexible conduit 172 connected to the port 120 of the valve 94. The pivot pin 40 (Figs. 1 and 13) for the fluid pressure cylinder 42 may conveniently serve as the supporting means for a strap 176 holding the two conduits 170 and 172 in close proximity to the post 24. A flexible conduit 180 is used to connect the port 110 of the valve chamber 104 to the upper port connection 182 (Fig. 1) of the vertical cylinder 42. A second flexible conduit 184 is used to connect the port 112 with the bottom end of the cylinder 42. The port 106 of the valve chamber 102 is connected by a conduit 186 to the end of the horizontal cylinder 36 most removed from the column 24. The port 108 is connected by a flexible conduit 188 to the other or piston rod end of the cylinder 36.

As will be seen in Fig. 1, two control devices 200 and 202 are mounted on a plate 204 on the left side of the gun adapter frame 12. As these two devices are similar to each other, only one of them (200) will be described in detail. It will be noted, however, that in the particular arrangement shown, the device 202 is in a position which is the reverse of that in which device 200 is placed. The details of the control device 200 are illustrated in Figs. 2 to 9 inclusive and in Fig. 12.

As seen in Fig. 3, the control device 200 has a front plate 206 and a back plate 208 both plates being fastened to the device by suitable screws 210 and 212, respectively. The screws 212 also serve as a means of supporting the control device 200 upon the plate 204. The body of the control device comprises a top horizontal plate 214, an intermediate plate 216 and a bottom plate 218. The plates 214 and 216 are separated by spacer blocks 220 and 222 and the plates 216 and 218 are separated by spaced blocks 224 and 226. Bolts 228 and 230 are utilized to hold the parts in assembled relation. The upper plate 214 (Fig. 7) has a vertical and square portion 232 which is vertically drilled and threaded for the reception of a recessed piston 234 (Fig. 7), a spring 236, and a threaded plug 240. The parts are so related that the piston or plunger 234 is urged against a block 244 by the spring 236 and the pressure of the spring can be adjusted by rotating the threaded plug 240. Between the plates 214 and 216 the block 244 is mounted and guided for sliding ac-

tion and this block carries a pin 246 pivoted therein (Fig. 8) and the reduced end 248 of the pin serves as a bearing for a vertical lever 250. A vertical pin 252 is located in the middle of the block 244 serving as a positive stop for two opposed horizontal plungers 254 and 256. These plungers are biased toward the pin 252 by two springs 258 and 260 held in place by a U-shaped member 262. The block 244 is properly recessed at both ends to permit movement of the U-shaped member 262 and also to permit the insertion of the plungers 254 and 256 as well as their springs. A pin 270 is journaled within the pin 246 and is fastened at 272 to a forked lever 274. The upper end of the lever 274 is bent at right angles and extends through an arcuate slot 276 in the block 244 toward the pin 252 and between the plungers 254 and 256. The upper end of the lever 274 is of the same width as the pin 252. The lower or forked end of the forked lever 274 engages a short pin 278 of a peculiarly shaped locking element separately illustrated in Fig. 12. It will be noted that this element carries a cross piece 280 which, when in assembled relation, is adapted to slide on the inner vertical side of the vertical or front face plate 206. This element also carries a rectangular slot 282 for engaging three sides of the plate 218 and a slotted arm 284 is so formed as to engage a pin 286 extending from the lower end of the vertical lever 250.

In the operation of the above-described control mechanism the gunner steadies and orients himself by holding the rigid handle 52 with his right hand and with his left hand he is enabled to control the application of power and bring about the required changes in elevation and azimuth by means of the handle or shield-like member 70.

In the event that the gunner desires to elevate the barrel of the gun 10 he will rotate the handle 70 a slight amount in a clockwise direction about the crosspin 62, as viewed in Fig. 1. As a consequence, rod 82 will be shifted to the left and so turn the arm 100 of the dual valve 94 that the valve stem 160 will be lowered. The lowering is by cam action of the pin and inclined slot arrangement at the bottom of the valve stem. Pressure fluid will enter through the conduit 170, inlet port 124, passage 122, and chamber 104 to pass by the valve land 164 into the port 112 and then through the flexible conduit 184 into the lower end of the cylinder 42. At the same time, fluid will be exhausted from the upper end of the cylinder 42 by way of the conduit 180, port 110, the chamber above valve land 162, passages 118 and 114, port 120 and conduit 172. As a consequence, the piston rod 44 will rise and the gun barrel will elevate as the gun adapter frame 12 rotates about the pins or trunnions 14 and 16.

If the gunner desires to depress the barrel of the gun 10 he will rotate the handle 70 in a counterclockwise direction about the pin 62 as viewed in Fig. 1, with the result that the valve stem 160 (by cam action of the pin and inclined slots) will rise and pressure fluid will be shut off from port 112 and will flow by the land 162 and through the port 110 and conduit 180 into the top of the cylinder 42 and pull the gun barrel down.

In the event the operator desires to swing the gun muzzle to the right he will rotate the handle 70 about rod 60 and in a clockwise direction, as viewed in Fig. 10, with the result that the rod 68 will be pulled to the right and the valve stem 136 will be lowered by cam action of inclined slots 145 on the pin 142. In such event pressure fluid will pass from the passage 122 into chamber 102

(between the valve lands) and then into the port 106 and through the conduit 183 into one end of the cylinder 36. The cylinder 36, being fastened to the nonrotatable bracket 30 by the pins 34 and 35, will remain stationary except for a slight pivotal action, and the piston 38, with the gun barrel will rotate to the right with the gun post 24 as a center. The piston rod 32, through pin 33, will pull the arm 29 (and therefore the gun) to give the desired rotation. At the same time, fluid pressure will be exhausted from the other side of the piston 38 through conduit 186, port 106, port 120 and conduit 172.

A counterclockwise rotation of the handle 70 as viewed in Fig. 10 will bring about a reverse 15 relative motion of the piston 38 and cylinder 36, causing the gun barrel to move to the left.

It will be understood that in the operation of the dual valve 94 the fluid pressure is directed from the relatively high pressure chamber between the valve lands of each valve stem to perform the work in training the gun and that both end spaces of each of the chambers 102 and 104 are filled with fluid at a relatively low pressure and communicate at all times with the flexible exhaust conduit 172.

The operation of the apparatus as such operation is described up to this point results in a direct control of the rate at which power is applied but the operator is aided considerably and the main purpose of the invention is achieved by the modifying action of the two control devices 200 and 202. The azimuth control of the gun, as already described, is by means of the rod 68. The control of the gun in elevation is by means of the rod 82. The control device 200 is such as to modify the motion of the rod 68 and the action of the control device 202 is to modify the motion of the rod 82. The slot 86 of the block 84 on the rod 68 engages a round ended pin 290 on the upper end of the lever 250 of the control device 200. The slot 96 of the block 94 on rod 82 engages a similar round ended pin on the lower end of the vertical lever of the control device 202.

If the rod 68 is moved to the right, as shown in Fig. 1, the engagement of the slot 86 with the pin 290 of the lever 250 will cause the pin 290 of lever 250 on device 200 to rotate (clockwise as viewed in Figs. 1 and 5) about the pin 286 as a center a distance which may be said to be equal to $2X$ (Fig. 5). This results in a given rate of rotation by power of the gun barrel in azimuth. As the gun barrel is swung at a rate sufficient to attain a line of fire on a moving target, it is essential that its rate of travel be reduced in order to prevent an overtravel or a rate which exceeds that requisite for maintaining the line of fire accurately on the target. It will be appreciated that the gun barrel must "catch up with" the target and then "keep up with" or "stay with" the target. The distance of " $2X$ " referred to above and indicated in Fig. 5 may vary from a very small amount up to a maximum, the maximum amount dependent upon the sizes and proportions of the parts of the control device 200. With such movement of a distance of " $2X$ " by the pin 290 (from position "A" to position "B," as shown in Fig. 5), the valve stem 136 will move downwardly a corresponding distance causing the gun barrel to swing to the right at a rate proportional to the distance " $2X$ ".

While attaining and also while maintaining the lever 250 in the position "B," the operator is

conscious of overcoming a tendency on the part of the handle to return toward its valve closing position. This tendency is due to the compression of springs 258 and 260 (Fig. 9) as the plunger 254 is moved to the right by the upper curved end of the forked lever 274. It will be understood that when pin 290 is moved to the right the lever or link 250 at first tends to pivot about the bearing 248 (Fig. 8). This tendency causes a force to be exerted by pin 286 upon the forked end 284 (Fig. 12) of the locking element. This force tips the slot 282 slightly with a resulting locking action on the plate 218. As the pin 286 cannot move because of the locking action, the lever 250 will then rotate about it to position B. As the short pin 278 is likewise locked in position, the forked lever 274 will rotate with the pin 270 (Fig. 8) as a pivot within the block 244. As a consequence, movement of the lever 250 will cause the block 244 to slide to the right between guide plates 214 and 216. The rotation of the forked lever 274 results in the compression of springs 258 and 260 as referred to above. The plunger 254 will directly compress spring 258 and as plunger 254 cannot move to the right (Fig. 9) because of the pin 252, the U-shaped member 262 will move to the right compressing the spring 260.

In order to avoid an "overtravel" of the target, the operator will desire to reduce the rate at which his gun barrel is swinging in azimuth. He is aided in this regard by the action of the device 200 which tends, by spring action, to reduce any initial movement of the rod 68 and the azimuth valve stem 136 (Fig. 11). He relaxes his hold or restraint on the tendency of the handle 70 to return toward valve closing position and the plunger 254 is immediately forced against the vertical pin 252 by the action of one of the centering springs 258 and 260. If the gun is being swung to the right, then it will be the spring 258 which causes the return; if to the left it will be spring 260. This return action causes the forked lever 274 to assume a new vertical position. This position is illustrated in Fig. 5 by the dotted lines representing the lower end of that lever. As the pin 278 is in alignment with the plate 218 and its movement will not tip the slot 282, the locking element will freely slide on the plate 218 to a new position and the lever 250 will assume the position "C" (Fig. 5). As this occurs, the valve land 140 is closed to one-half the original opening into port 106 produced by the initial movement of the handle 70. The principle of operation need not be limited to a one-half return of an initial movement but the specific construction shown is so limited as the pin 272 (Fig. 5) is half way between pins 286 and 290. When this condition has been achieved, the valve stem 136 will be held stationary so long as the operator does not exert sufficient force through the handle 70 to overcome a frictional resistance to movement of the block 244 between its guides 214 and 216 and the centering effect of the plunger springs 258 and 260.

If the gun barrel is to be swung to the gunner's left, then the operator turns the handle 70 in the counterclockwise direction as viewed in Fig. 10. The lever 250 of the control device 200 is swung to the left instead of to the right and springs 258 and 260 again function to aid the operator in reducing the initial valve opening.

The control device 202 operates in the same manner as does device 200 but is used in training the gun in elevation and the two devices cooperate to give accurate easy control as the gun barrel is swung in planes other than the horizontal and vertical planes.

The constant speed tracking of the gun (during the assumption of an "X" position by the lever or levers 250 in each or both of the control devices) may be stopped or adjusted by the operator through movement of the control handle 70 at any time if he exerts sufficient force to overcome the velocity control produced by the above-described mechanism. It will be seen that each valve is allowed to close to one-half of the original opening irrespective of the magnitude of that opening and that the mechanism causes the gun to track at a constant speed which is proportional to the original opening. There is no uncertainty as to operation because of friction between the parts as the jaws of slot 282 in the locking member positively grip the plate 218 whenever a horizontal force is exerted against pin 286. It will also be seen that in making an initial correction which entails the closing (instead of the opening of a valve as referred to above), the same automatic operation is achieved—i. e.—if the valve is initially closed an amount expressed as "2X," that closure will be automatically reduced to an amount expressed as "X" as the reduction is permitted by the operator.

As seen in Fig. 5, the bearing 272 is mid-way between the pins 290 and 286. This determines the proportion of the original valve opening to which a given valve is closed by the control device linked thereto. It will be understood that the above-referred-to proportion need not be in the ratio of one to two but may be varied as desired by suitable changes in the design or proportions of the control device parts or other parts of the control system.

The second embodiment of the invention is shown in Figs. 15 to 26 inclusive.

In Fig. 15 a conventional gun and mount 300 are shown as installed in the tail of an airplane permitting the gun to be trained in azimuth about a rotatable vertical column 302 and in elevation about horizontal trunnions 304 (only one is shown) upon which the gun adapter is supported. Details regarding the mount per se are not specifically described as they form no part of the present invention. It may be stated, however, that a standard reflex sight 306 is utilized in training the gun and that suitable linkages 308 and 310 are provided whereby the line of sight is maintained in proper relation with the barrel of the gun. The details regarding the sight and its linkages are likewise not specifically described as they form no part of the present invention. The fuselage 312 of the airplane in which the gun is placed is provided with a rigid frame or shelf 314 to which a flange member 316 is bolted to serve as the supporting member for a control mechanism generally indicated as 318.

The control mechanism 318 comprises a casing 320 suspended from the flange member 316 by four bolts 322 which are provided with nuts 324 within the casing 320 to support the latter. Two bolts 326 pass through the flange 316 as well as the top of the casing 320 and are threaded into lugs 328 integral with an oddly shaped piece 330 of dielectric material such as plastic.

The oddly shaped plastic piece 330 has integral and inclined flanges 332 and 334 which are rigid-

ly fastened to the casing of a motor 336 by means of two screws 338 and 340. The flanges 332 and 334 are joined around one end of the motor 336 by an integral crossbar 342 (Figs. 16 and 17) supporting a stub shaft 343 upon which is journaled a gear 344 in mesh with a gear 346 on the shaft of the motor 336.

The motor 336 has a boss 348 on the bottom of its casing to which the bottom of the casing 320 is attached by means of two screws 350 only one of which is shown. A switch 352 is provided on the side of the casing 320 for the control of the current leading to the motor 336.

The oddly shaped plastic member 330 has two main portions 360 and 362 (Fig. 19) and these two portions are joined by a cylindrical part 364. The portion 360 has four annularly spaced chambers 366 each of which is slotted at one end for the reception of a pin 368 integral with a plunger head 370 and a plunger stem 372. A coil spring 374 surrounds the plunger stem 372 and is arranged to tend to move the plunger head 370 toward the right as viewed in Figs. 17 and 19. Each plunger stem 372 extends to the left through the wall of the portion 360 and in slideable relation thereto. Each plunger head 370 is beveled at 380 to present a ridge 382 which is radial to the longitudinal center of the oddly shaped plastic member 330. A flat brass spring 384 is maintained in sliding contact with each pin 368 by a fastening device comprising a screw 386 and a lock nut 388 within a cup 390 formed on the portion 360.

The main portion 362 of the plastic 330 is provided with four spaced chambers 400 each of which is in alignment with a corresponding passage 366 of the portion 360. Each passage 400 is reduced in diameter at its right end 402, as viewed in Fig. 19, and thereby forms a restraining means for one end of a coil spring 404 within the passage 400. Each passage 400 has inserted within it a slideable tube 406 an enlarged portion of which is joined to a smaller diameter portion by a partition 408, and the right side of the partition bears against the coil spring 404, and the left side of the partition 408 restrains a plunger 410 from moving toward the right. Each plunger 410 is retained in position by the action of a coil spring 412 compressed between a shoulder 411 of that plunger 410 and a conical flanged cap 414 inserted within its tube 406. Each tube 406 is restrained against extensive movement toward the left (Fig. 19) by a spring clip 416 encircling it and engaging the shoulder formed by the reduced portion 402 of the chamber 400 in which the tube 406 moves. The shoulder 411 is an integral part of each plunger or contact rod 410 slideable within the tube 406. As may be seen in Fig. 19 the plunger stems 372 with their aligned plungers 410 constitute four sets of electrical contact points and that the range of movement permitted by the springs 374, 404 and 412 is sufficient to give a substantial clearance between the contact points. The plastic member 330 is bored at its axial center to receive and suitably journal a shaft 430, and the bottom of the bore retains a light spring 432 tending to move the shaft 430 to the right. A gear 434 of dielectric material is keyed at 436 to the shaft 430 and is provided with an integral annular cam 438 arranged to bear against the ridges 382 of the four plunger heads 370. The casing 320 is closed at one end by means of a plate 440 bolted thereto at 441, 442 and 443 and this plate 440 has a set screw 444 screwed into it and held in adjusted position

thereon by means of a nut 446. This set screw 444 serves to limit the movement of the shaft 430 and the gear 434 to the right under the influence of spring 432 or the plunger head springs 374.

A portion of one end of the casing 320 is enlarged into a partly spherical form and is provided with openings 450 and 452 (Fig. 17) through which stub shafts 454 and 456 protrude and support handles 458 and 460. The stub shafts 454 and 456 comprise a part of the gimbals structure for supporting the handles for universal movement and they rotate within bearings of a ring 462 (Fig. 20) which in its turn is pivoted on pins 464 and 466, the latter pins being mounted within bosses 468 and 470 formed on the casing 320. The handle stub shafts 454 and 456 (Fig. 17) are integral with a wobble element or plate 472 (Fig. 20) this plate having a flat surface 473 (Figs. 17, 24 and 25) on one side and contacting the points of the four conical caps 414. The other side of the wobble element or plate 472 has a recessed hub 474 into which is telescopically mounted a cup 476 with a spring 478 therein, this spring being under compression and tending to hold the cup with a conical recess 480 in the end thereof in engagement with a ball 482 pressed against the inside spherical surface of the casing 320 and retained in position by a cylindrical flange 484 formed on a disk 486. The surface of the disk 486 has a spherical curvature contacting the inside surface of the casing 320 with a degree of friction which may be varied. Such variation may be produced by three screws 490 (only two of which are shown) which pass through the wall of the casing 320 and engage ears of an inner ring 492, this latter ring in turn pressing an annular adjacent ring 494 against the disk 486. Undue displacement of the ring 494 is prevented by lips 495 (Fig. 24) on the ring 492. The cup 476 has an annular flange 500 the surface of which has the same center of curvature as does the spherical enlargement of the casing 320. A small hole 498 in the cup 476 serves as a vent.

The end plate 448 of the casing 320 has a threaded connection 502 (Fig. 15) to which an electric conduit 504 is attached and which conduit leads to a connector box 506. A conduit 508 leads from some source of electric power supply into the bottom of the connector box 506. A flexible conduit 510 is also connected to the box 506 at one end and at its other end leads to a threaded connection 512 attached to a solenoid-operated valve generally indicated at 514 (Fig. 21). This valve is rigidly mounted parallel to and against a vertical or elevation cylinder 516 (Fig. 15) which cylinder is pivotally mounted on a shaft 518 protruding horizontally from the gun mount column 302. The cylinder 516 is fluid-pressure operated and is similar to the elevation cylinder of the above-referred-to first embodiment of the invention. It is provided with a vertical piston 520 pivoted at 522 to a lever 524 keyed to the pivot or trunnion 304 of the gun adapter. Within the cylinder 516 the enclosed chamber above the piston (not shown) is connected by means of a pipe 526 to a port 528 of the solenoid valve 514. A second pipe 530 connects the chamber beneath the piston within the cylinder 516 to a port 532 of the valve 514. A flexible conduit 534 for fluid under pressure leads from a source of pressure fluid supply and is connected to a T connection 536 one branch of which is connected to a flexible conduit 538 leading to a port 540 of the valve 514. A second branch 542 leads

from the T connection 536 to a second solenoid operated valve 542. This second solenoid operated valve 542 is similar in all respects to the valve 514 except that it is placed in a horizontal plane and is so connected as to control the operation of a power cylinder 544 for training the gun in azimuth. The latter cylinder has a horizontal piston rod 546 which is pivoted to a lever 548 for rotating the gun mount 300 in azimuth. As will be understood, the power cylinder 544 and its controlling solenoid operated valve 542 are arranged upon the frame or floor of the airplane fuselage to pivot slightly in a horizontal plane to permit the swinging of the arm 546. Details 15 regarding the mounting of the power cylinder 544 relative to the gun mount and the airplane structure are not illustrated as such mounting may be easily provided and its specific form is immaterial in so far as the present invention is concerned. 20 An exhaust conduit 550 which is flexible, leads from a port 552 of the valve 514 to a T connection 554 having two branches one of which is connected by a flexible conduit 556 to the exhaust fluid port of the valve 542 (like port 552 of valve 25 514) and the other of which is connected by a flexible conduit 558 to the return line of the fluid pressure system (of the airplane, for example). A fourth electrical conduit 560 is connected to the box 506 and leads to the solenoid control valve 542.

As stated above, the solenoid operated valves 514 and 542 are similar in construction. Accordingly only one of them, valve 514, is herein illustrated and described in detail. This valve 514 is described in detail and shown in Figs. 21, 22 and 23. The fluid pressure portion or main body 570 of the valve 514 has an axial chamber into which a sleeve member 572 is tightly fitted, this sleeve member 572 being open at both ends and having cut out portions at its ends for communication with an upper annular chamber 574 and a lower annular chamber 576. The sleeve 572 also has radial ports 577 communicating with an annular chamber 578 of the valve body 570. The port 528 leads into the annular chamber 578. The port 540 in the body 570 communicates by means of an annular chamber 580 with a number of radial ports 582 leading through a midportion of the sleeve 572 into a chamber 584 surrounding a valve stem 586 and extending from a valve land 588 to a valve land 590. The valve land 588 corresponds with the radial ports 577 and the valve land 590 corresponds with the radial ports 592. The latter ports lead to an annular chamber 594 which communicates with port 532 of the valve body 570. The lower end of the body 570 is closed by means of a plate 596 but this plate has an axial opening 598 into which a depending rod 600 extends in slidable relation. This rod 600 is attached to the valve stem 586 at one end and at its other end is attached to an iron solenoid plunger 602 which is in slidable relation to the inner casing 604 of the solenoid coils 606. It is preferable that the rod 600 be loosely attached to its contiguous parts for ease of assembly and avoidance of difficulties due to possible misalignment. The bottom end of the solenoid casing is enclosed by a plate 608 through which an adjustable screw 610 is threaded and held in adjusted position by a lock nut 612. The screw 610 serves to maintain a centering spring 613 within a recess of the solenoid plunger 602 under suitable compression. The plate 608 bears a threaded boss 614 to which is threaded a protecting cap 616. The plate 608, cap 616 and solenoid structure are retained in

position upon the valve body 570 by four bolts 620. An annular chamber 622 (Fig. 22) is within the casing of the solenoid and beneath the coils thereof to make room for the connecting wires to the solenoids. These wires are not shown but are led by means of a conduit 624 from the chamber 622 up to and within the rectangular portion 626 of the upper solenoid casing 630 of the same valve 514. The solenoid 630 is the same as the lower solenoid except for the rectangular portion 626 of the solenoid casing and the threaded connection 512. The annular chambers 574 and 576 of the valve body 570 communicate by means of a channel 632 (Fig. 21) with the port 552.

Figs. 16 and 17 do not show the wiring but the connections may be readily understood from the disclosure of Fig. 26. The wires A and B (Fig. 26) connect the solenoid coils of the elevation control valve 514 to the spring contacts 384 of the upper and lower plungers 372 respectively in the plastic piece 330. Each of the wires C and D connects one solenoid coil of the azimuth control valve 542 to a spring contact 384 of one of the side and opposite plungers 372.

It is to be understood that the gun may be fired by means of a foot treadle (not shown) or by buttons 650 and 651 (Fig. 17) on the handles 458 and 460. The wiring for firing the guns is not illustrated as it forms no part of the present invention.

In operating the gun mount of Fig. 15, the gunner will first close the switch 352. As a consequence, the motor 336 will continuously rotate the dielectric gear 434 and its integral cam 438. The cam is so shaped that the plungers 372 will reciprocate rapidly relative to the plastic piece 330, the ridges 380 sliding on the annular cam surface and contact therewith being maintained by the springs 374. Normally, that is, with the gun not swinging in either azimuth or elevation, there is a minimum of contact between the plungers 372 and the plungers 410 as the former reciprocate under the action of the cam 438. This minimum of contact keeps the solenoid valves "alive" for action without disturbing the guns.

Should it be desired to swing the gun barrel to the left in azimuth, the handles or grips 458 and 460 are rotated slightly and in a counter-clockwise direction as viewed in Fig. 17. The plate 472 will be likewise rotated and in Fig. 24 it is shown as rotated ten degree from a normal position. At that time the pair of plungers 372 which controls the azimuth valve 542 and which plungers are spaced 180° apart—will be alternately reciprocated, there being one reciprocation of each plunger for each revolution of the cam 438. Such reciprocation of the azimuth plungers 372 will cause them alternately to come in contact with the two collinear plungers 410. This contact makes a ground connection through the plate 472 and other parts including the casing 320 and bracket 316. Excess motion of the plungers 372 is taken up by the sliding of the plungers 410 against the springs 412. It will be understood that the greater the displacement of the plate 472 from the normal position (perpendicular to the direction of reciprocation of the plungers), the greater will be the time during which a given plunger 410 remains in contact with its collinear plunger 372. When the displacement of the grips 458 and 460 is at its maximum, either in azimuth or elevation control, the appropriate plungers will be in contact to maintain a constant and maximum current to flow to ground from the appro-

priate solenoid coil. When the displacement of the plate 472 is ten degrees as in Fig. 24, a limited amount of pulsating current will be caused to flow through the coil of the solenoid H and wire 5 to ground with the result that the valve spindle of valve 542 will be shifted to admit fluid pressure to the appropriate end of the azimuth motor cylinder 544 to move the gun barrel at a limited rate to the left. The coil of solenoid G would be energized if the gun barrel were to be swung to the right.

The action is smooth for it will be noted that the valve spindle lands on their exhaust sides are tapered providing a cushioning back pressure 15 of the operating fluid. It will also be seen that the flow of pressure fluid to cause movement of the power piston in either direction is obtained by energizing the appropriate solenoid coil and that the greater the current flowing through the coil the greater will be the opening of the valve controlled by the coil. The contacts within the casing 320 serve to vary the amount of pulsating or interrupted direct current passing through a given solenoid coil and that amount will depend 20 upon the relation between the time magnitude of the pulsations and that of the intervals between pulses.

Rotation of the grips or handles 458 and 460 in a counterclockwise direction as viewed in Fig. 30 16 will cause the gun barrel to rise in elevation at a rate proportional to the amount of rotation of the grips. The operation is the same as in training the gun in azimuth but current is passed through the coil of the solenoid F (Fig. 26) thereby raising the valve spindle of valve 514 and admitting pressure fluid to the motor cylinder 516 thereby pulling the piston rod 520 downwardly at a certain rate. The gun barrel will therefore rise at a rate dependent upon the angle 35 to which the grips or handles are turned from their normal position. Rotation of the grips in the opposite or clockwise direction (Fig. 15 or 16) will cause the gun barrel to drop at a rate dependent upon the degree of the rotation. The gun barrel will be depressed because of the energizing of the coil of solenoid E and the lowering 40 of the valve spindle.

The plastic or dielectric gear 434 with its integral cam 438 may be moved and adjusted toward and away from the plastic piece 330 by means of the screw 444 and nut 446. By appropriate adjustment, the collinear plungers may be made to contact for an instant during each cycle thereby causing a slight dithering action 45 of the valve. In this way control sensitivity may be increased over the no-dither condition.

The design of the electric control device is such 50 that the control may be effective simultaneously in both azimuth and elevation movements of the gun and that control is operated with ease and accuracy. In order to aid the operator and secure the advantage derived in the use of the first form or embodiment of the invention disclosed, however, the plate 472 is provided with means already described which supply a tendency on the part of the plate 472 to return or rotate half way back to the normal or initial position after being displaced. In the second embodiment of the invention, therefore, the operator is aided 55 that he may with facility "catch up" to a moving target and yet avoid an "overtravel" of the target. The ball 482 and the cup 476 constitute the main parts of the aiding means referred to.

Assuming that the gunner moves the plate 472 70 ten degrees as an initial displacement (shown in

Fig. 24) in order to swing the gun barrel to the left at an accelerated rate to "catch up" with a target, he will then desire to reduce the rate and "stay on" the target. He will relax his grip on the handles and the spring 478 will aid him to reduce the initial rate.

Figs. 24 and 25 illustrate the operation of the aiding means. The initial movement of the plate 472 through an angle of ten degrees (the center line moving from position X to position Y) results in the accelerated rate of movement of the gun barrel. It also results in the center of the sphere 482 moving from a position on line X to a position on line Z as in Fig. 24. The sphere 482 rolls on the inner surface of the spherical shell and the wall of the conical recess 480 of the cup 476. The wall of the recess 480 is at an angle and the initial simultaneous rotation of ten degrees of the plate 472 and of five degrees of the center of the sphere or ball 482 causes the cup 476 to slide into the recessed hub 474 and compress the spring 478. The sphere 482 bodily moves only five degrees as the cup 476 moves ten degrees and this can be understood by comparing the action with that of the vehicle wheel—the top of the wheel moves twice as fast or far as does the hub. The hole 496 avoids air entrapment. The disk 486 is carried along with the ball 482 a distance of five degrees and its movement is resisted by the friction between it and the inner wall of the casing 320. This friction is adjustable by means of screws 490 as heretofore stated. The gunner must therefore overcome the friction between the disk 486 and the casing 320 and also compress the spring 478 in order to achieve his desired initial rate of gun movement to "catch up" with the target.

Desiring to reduce the rate of gun movement, the gunner will relax his slight exertions upon the grips or handles 458 and 460. As a result, the spring 478 will expand and the wall of the recess 480 will slide on the surface of the ball 482. This sliding action is certain because of the conical wall of the recess 480—i. e.—bodily movement or retraction of the sphere 482 is prevented because of the retention of the friction between the inner wall of the casing 320 and the disc 486 whereas release of the handles by the operator reduces the pressure and friction between the sphere and the surface 480. The center of the ball 482 will not be displaced from its position on line Z because of the undiminished friction between disk 486 and the casing 320. As this follow-up action occurs the plate 472 assumes the position shown in Fig. 25 and is caused to remain in this position by the friction between the washer or disk 486 and the casing 320 as long as the operator does not exert sufficient force on the grips 458 and 460 to overcome this friction. With the parts positioned as in Fig. 25, the initial valve opening has been reduced, thereby aiding the gunner to avoid the undesired "overtravel" of the target.

As in the case of the first embodiment of the invention herein disclosed, the controlling means of Fig. 15 grasped by the gunner is allowed to return through one-half of its original angle of displacement whether the original displacement be for opening or for closing the valves or a valve. The gun is therefore caused to track at a constant velocity which is proportional to one-half the original or initial displacement of the control means and this tracking will continue until additional corrections are made by the operator. Such added corrections may be made by the operator at any time through exertion of sufficient

force on the grips 458 and 460 to overcome the action of the device.

It will be understood that the proportions of the parts in Figs. 24 and 25 are such that the follow-up action or aid in correcting the rate of tracking is limited to a desired range of valve opening. If the valve or valves were opened beyond this range, due to the application of sufficient force by the gunner on the grips, the ball 482 would emerge from the recess 480 and roll upon the spherical surface of the flange 500. In such a case the ball 482 would have no effect and the opening or closing of the valve 514 or 512 would be proportional to the displacement of the grips 458 and 460. Such direct proportional control is available to the operator at any time.

The control mechanism of Figs. 15 to 26 is particularly advantageous because it is very sensitive and accurate. This result occurs because the control may be said to be "alive" at all times. The possible dither of the valves may not be appreciable and yet the control will respond promptly. The mechanism operates efficiently whether the valve lands 588 and 590 are designed for no lap or for a slightly positive lap. To illustrate the delicacy of the control it may be said that valves of Figs. 21 and 22 have been used in gun mount control installations and the valves have been closed and opened in fine increments all within the full range of approximately $\frac{1}{8}$ " to $\frac{1}{16}$ " distance of travel of the valve lands from fully open position in one direction to fully open position in the other direction.

Having fully described my invention, what I claim as new and desire to secure by Letters Patent of the United States is:

1. Control apparatus for a fluid pressure system comprising a valve element for said system and operating handle means, electrical means connecting said handle means and the valve element for transmitting a movement from the handle means to the valve element, said electrical means comprising two sets of contact elements, the contact elements of one set being in substantial alignment with corresponding contact elements of the other set, power operated cam means to vary the distance between the ends of the aligned contact elements, means attached to the handle means for resiliently moving one set of contact elements toward the other set upon movement of the handle means, solenoid means for operating said valve element, and an electrical circuit controlled by contact of the two sets of contact elements and arranged to actuate the said solenoid means.

2. Control apparatus for a fluid pressure system comprising a valve element for said system and a combined operating handle means and wobble element mounted for universal movement, means connecting said wobble element to said valve element for transmitting an initial movement of the handle means to the valve element, a spherical section at one side of the wobble element, a spherical washer in frictional engagement with the concave side of said spherical section, a ball retained by said spherical washer and in rolling contact with said spherical section and a plunger with a conical seat engaging said ball, said plunger being mounted on the wobble element and resiliently pressed against the ball.

3. Control apparatus for a fluid pressure system comprising a valve for said system and a manual control handle for said valve, linkages for transmitting an initial movement from said handle to said valve, and a control unit with a

sliding block, said unit having a control lever with one end pivoted to said linkages and an intermediate portion to said block, a locking member pivoted to the other end of said control lever, guiding means upon which said block and locking member may slide and a rocking lever pivoted to the block with one end of said rocking lever engaging the locking member, the other end of said rocking lever being resiliently positioned between centering springs within the said block, the arrangement being such that said initial movement is continued to a more limited extent and in the reverse direction by said control unit when manual control of said handle is relaxed.

4. A gun mount having a fluid pressure system for training a gun in azimuth and elevation, control apparatus for said system comprising a handle linked for unitary operation of two valves in said system and one control unit associated with each valve, said control unit including a sliding block and a locking member with guiding means for said block and member, a control lever pivoted to said block and linked to the handle and valve, a rocking lever with an intermediate portion pivoted to said block and with one end of said rocking lever being pivotally connected to the locking member, the other end of said rocking lever being resiliently positioned by an extension thereof located between centering springs with-

in the sliding block, the axes of the rocking lever pivots being transverse to the said guiding means, and the arrangement being such that an initial movement of either valve by means of the said handle is continued to a lesser extent and in a reverse direction by said control unit when manual control of said handle is relaxed.

FRED C. EASTMAN.
